TAPE MOISTENING DEVICE

Alfred Burckhardt, Stamford, Conn., assignor to
 Pitney-Bowes Postage Meter Co., Stamford,
 Conn., a corporation of Delaware

Application October 9, 1943, Serial No. 505,589

4 Claims. (Cl. 91—43)

This invention relates to a device for use in the moistening of the gummed surface of tape and includes manually adjustable means for permitting the reception of tape either as moistened or unmoistened.

It is the principal object of the invention to provide manually controlled shielding and pressure members which are movable relative to a moistening member in such manner that the shielding and pressure members may be adjusted simultaneously to either a moistening or a non-moistening position.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawing, wherein:

Fig. 1 is a perspective view of the moistening device with tape passing therethrough;

Fig. 2 is a front elevational view of Fig. 1 on an enlarged scale;

Fig. 3 is a vertical sectional view, on a further enlarged scale, of Fig. 2 and showing the device in a non-moistening position; and

Fig. 4 is a view similar to Fig. 3, showing the moistening device in a tape moistening position.

Referring to the drawing in detail, the moistening device generally comprises a supporting member 10, a capillary slotted tube 11, a shield 12, and a pressure member 13. The slotted tube 11 is secured to the supporting member 10 in a horizontally disposed position by means of a screw 14, and the shield 12 is pivotally supported thereon so that it will be adapted to rock about the axis of the tube 11. A rod 15, also secured to the supporting member 10, is horizontally positioned above the slotted tube 11 and is adapted to support the pressure member 13 thereon in such manner that the said pressure member will rock about the axis of the rod 15. By means of a spring 16, the pressure member 13 is adapted to be urged toward the shield 12 and tube 11.

The shield 12 has a depression 17 formed therein along one edge thereof, and is provided with a handle 18, said handle projecting sidewardly through a slot 19 in the supporting member 10. Shoulders 21—21 on said shield 12 form an abutment against which the pressure member 13 is

urged by the spring 16, when the shield and pressure members are in the non-moistening position of Fig. 3. The pressure member is secured in place on the rod 15 by means of a screw 22 and lock washer 23.

The moistening member 11 has a longitudinal opening 24 therein and a capillary slot 25. Said opening 24 and slot 25 are supplied with liquid through a connecting tube 27 from any convenient source of liquid supply. The arrangement of said capillary tube provides a film of liquid at the exposed surface of the slot, which film is adapted to be engaged by the gummed surface of a strip of gummed tape when moistening of the tape is to be effected. Upon drawing the tape across the slot sufficient liquid adheres to the gummed surface to completely moisten the said surface and thus provide good adhesive or sealing qualities.

When the device is arranged according to the position shown in Fig. 3, it will be seen that the shield 12 projects over the moistening slot 25 in the tube 11, and that the pressure member 13 is spaced from the shield 12 to provide a guide opening through which the tape passes, while shielded from the moistening slot. The tape is unmoistened when received in this manner.

When the device is arranged according to the position of Fig. 4, the shield 12 is withdrawn to expose the slot 25, and the pressure member 13 is urged toward the slot by the spring 16. This will effect engagement of the gummed surface of the tape with the slot 25, and when the tape is withdrawn, the gummed surface will be moistened.

By adjustment of the handle 18 through the length of the slot 19, the device may be set in either a moistening or non-moistening position.

The tape may be received from any desired source or tape issuing device such as indicated generally at 26.

Having described the invention what is claimed is:

1. In a gummed tape moistening device, a moistening member having a liquid moistening surface disposed in the path of tape issued from a tape issuing device, a manually adjustable shield movable relative to the moistening surface of the moistening member to effect shielding or non-shielding of said moistening surface, and a pressure member movable with the shield to urge the tape against the moistening surface of the moistening member when the shield is in a non-shielding position.
2. In a gummed tape moistening device, a moistening member having a liquid moistening surface disposed in the path of tape issued from a tape issuing device, a manually adjustable shield movable relative to the moistening surface of the moistening member to effect shielding or non-shielding of said moistening surface, and a pressure member movable with the shield to urge the tape against the moistening surface of the moistening member when the shield is in a non-shielding position.

tening member having a liquid moistening surface disposed in the path of tape issued from a tape issuing device, a manually adjustable shield movable relative to the moistening surface of the moistening member to effect shielding or non-shielding of said moistening surface, a pressure member movable relative to the moistening surface of the moistener member, and means to effect simultaneous movement of the shield and pressure members.

3. In a gummed tape moistening device, a moistening member having a liquid moistening surface disposed in the path of tape issued from a tape issuing device, a manually adjustable shield having abutment shoulders and movable relative to the moistening surface of the moistening member to effect shielding or non-shielding of said moistening surface, a pressure member movable relative to the moistening surface of the moistener member, and means to normally urge the pressure member against said abutment shoulders when the shield is in a shielding position to provide a guide for the tape between the shield and

5 pressure member, and to urge the pressure member toward the moistening surface to thereby urge the gummed surface of the tape against the moistening surface when the shield is in a non-shielding position.

4. In a gummed tape moistening device, a moistening member having a liquid moistening surface disposed in the path of tape issued from a tape issuing device, a manually adjustable shield movable relative to the moistening surface of the moistening member to effect shielding or non-shielding of said moistening surface, a pressure member movable relative to the moistening surface and shield, and means to effect simultaneous movement of the pressure member and shield, whereby, during shielding of the moistening member, the pressure member and shield are spaced apart to form a guide through which the tape will move without effecting moistening, and during non-shielding of the moistener, the pressure member will urge the tape against the moistening surface to effect moistening of the tape.

ALFRED BURCKHARDT.
